UNITED STATES PATENT OFFICE.

THOMAS ROBSON AND WALTER GEORGE FISHER, OF ALLISTON, ONTARIO, CANADA.

SHOCK-LOADER.

No. 891,008.

Specification of Letters Patent. Patented June 16, 1908.

Application filed August 27, 1906, Serial No. 382,243. Renewed May 2, 1908. Serial No. 430,537.

To all whom it may concern:

Be it known that we, THOMAS ROBSON and WALTER GEORGE FISHER, both of the town of Alliston, in the county of Simcoe, in the Province of Ontario, Canada, have invented certain new and useful Improvements in Shock-Loaders, of which the following is the specification.

Our invention relates to improvements in shock loaders patented in the Dominion of Canada under No. 93458 on the 6th day of June, 1905, and the object of the present invention is first,—to provide an adequate means whereby the shock may be picked up without any liability of its being thrown away from the carrier prongs and the picking up elevator, and discharged from the elevator clear of the prongs in a proper position on to the elevating apron, secondly,—to provide a means whereby the machine may be prevented from tipping as the picking up elevator encounters the shock, thirdly,—to provide an improved arrangement of drive and clutch mechanism which will allow of a substantially horizontal rear apron being supported temporarily to act as a table in gathering scatter sheaves, and fourthly,—to provide a simple and secure means for holding the side elevator at any desired angle necessary to discharge the shock on to the wagon. To effect these objects we have constructed and arranged our machine with a suitable frame at the front of which is carried the inclined picking up elevator to the rear of which is located the horizontal apron at one side, and at one side of the latter the side elevator.

The machine is supported on a main driving wheel, an end wheel located substantially opposite to the main drive wheel on the opposite side of the machine, and leading wheels located well to the front and between the side of the picking up elevator and connected by a bar to the main frame opposite and in front of the elevator, all the parts being otherwise arranged and constructed as hereinafter more particularly explained.

Figure 1, is a perspective view of our machine complete, the elevator being intermediately broken away. Fig. 2, is a side sectional elevation through the center of the picking up elevator and horizontal apron. Fig. 3, is a plan; intermediately broken away. Fig. 4, is a back view of the machine showing the drive and means for raising and lowering the elevator, the frame carrying the horizontal apron being intermediately broken away.

Fig. 5, is a detail showing the means of withdrawing the picking up prongs beneath the guard strips.

In the drawings like letters of reference indicate corresponding parts in each figure.

A is the main frame which is substantially rectangular in form and it comprises the end bar A¹ and intermediate bar A², extending bar A³, opposite end bar A⁴, the front bar A⁵ extending from the bar A⁴ to the bar A², the bar A⁶ extending from the bar A³ to the bar A¹ and the rear bar A⁷ extending across the full width of the machine.

B are the side boards of the picker elevator and C C' are the top and bottom cross bars extending from side board to side board and carrying the guard strips D and D'. It will be noticed that the major portions of the guard strips D are inclined and straight. The top, however, is curved as indicated, being fastened at the extreme end to the bar C. The bottom is also curved in the form of a compound curve and fastened to the bar C'. The strip D' is differently formed from the strip D, the major portion being straight, but the upper portion being provided with a quicker curve D² of compound form which extends up above the curved top of the strip D and is fastened by a slotted lug and bolt D⁵ and D⁶ to the side bars B. The bottom of the strip D' is provided also with a quicker compound curve D³ and the extreme end is fastened to a cross bar D⁴.

E and E' are the top and bottom sprocket wheels respectively, which carry the end sprocket chains E². The sprocket wheels E and E' are carried by the shafts 2 and 3 respectively which are journaled in suitable bearings as indicated.

F is a guiding strip located to the rear of the sprocket chain E² and having a substantially crescent shaped upper end F'.

G is the back of the picking up elevator which extends from the bar C to the bar A⁶ to which it is secured.

H are cross bars between the side bars B designed to stiffen the elevator frame.

I are cross bars which carry the prongs I' and are connected to a link in the sprocket chain E² at the end by the pins I² which carry at their outer ends the rollers I³. Each bar I carries an arm I⁴ which extends in the direction of movement of the sprocket chains. The arm I⁴ is crank shaped and carries the rollers I⁵.

We may here state that both ends of the

bar are constructed alike and when we are describing one end we wish this to be understood.

5 E^3 are segmental plates secured to the sprocket wheel E and provided with arc shaped lateral projecting ends E^4 concentric to the center of the shaft 2 and laterally extending lugs E^5 .

10 I^6 are bosses formed on the bars I at the opposite side to the arm I^4 .

15 J is a sprocket wheel secured on the inner end of the shaft 3 and connected by a sprocket J' to a sprocket wheel J^2 secured on the shaft K. The hub of the sprocket wheel J^2 forms one portion of a clutch, and the other portion is formed by a collar J^3 of the usual form and having an annular groove J^x . In the annular groove J^x extends the pin on the end of the bell crank 4 which is pivoted on a bracket 5 attached to the cross bar A². The other opposite end of the bell crank is connected by a lever 7 to a lever 8 which coacts with a quadrant 6. The opposite end of the shaft K is provided with a gear pinion K' which meshes with an internal gear K² on the main wheel K³, the axle K⁴ of which is journaled in suitable bearings A^y and A^x. The drive therefore, of the picking up prongs will now be understood and the manner of throwing such drive into and out of gear, as by means of the lever 8 and its coacting parts hereinbefore referred to.

20 We shall now describe the movement of the prongs I' connected to the cross bars I carried by the sprocket chains E².

25 As the bars I ascend the arm comes in contact with the arc shaped projections E³ thereby raising the rolls I⁵ and tilting the bar so that the prongs are thrown on a backward incline as to direction of movement. As the sprocket wheel E continues to revolve the prongs gradually assume the position shown by dotted lines in Fig. 2, until they are entirely withdrawn within the guard strips D.

30 40 This backward tilting of the prongs serves to retard the motion of the shock so that it is discharged over the end of the strips D at a comparatively slow speed and thus deposited properly upon the apron L, the movement of which we shall presently describe. As the wheel E continues to revolve the tail I⁶ comes in contact with the projection E⁵ thereby

45 throwing the bar into position shown in full lines on the crescent shaped end of the guide bar F. As the bar continues to be carried around by the chain E² it is caused to assume the position shown at the back of the chain E² by means of the bar F. In this position the arm I⁴ is thrown with the roller I⁵

50 60 forwardly so that the prongs extend outwardly as they pass around the curved end D³, such curved end serving to act on the roller I⁵ so as to give the prongs a forward incline from base to tip. We find in practice 65 that this is the most advantageous position

they can assume to take hold of the shock or sheaves without striking against the guard strips D, and by these prongs the shock or sheaves are carried up over the guard strips and discharged as hereinbefore explained. 70

The apron L is carried on rollers journaled in bearings in the back G of the picking up elevator and the back G'. The spindle L' of the uppermost roller has secured on it a sprocket wheel L² through which the apron L 75 is driven in the direction indicated as hereinafter described.

80 M are the elevator side bars which are swung on the shaft L' journaled in suitable bearings on the frame at the discharge end of the apron L. The elevator consists of the bands N which carry the cross slats N' such band being carried on suitable end band wheels N² at each end, the band wheel N² at the lower end being secured on the shaft L². 85 The apron L and elevator N are driven as follows: O is a sprocket wheel secured on the end of the counter spindle O'. O² is an idler sprocket carried by a bracket O³ secured to the bar A⁷ of the frame. The bracket A⁷ 90 may be vertically adjusted as will appear from the drawing. P is a sprocket chain extending from the sprocket wheel O over the idler O² to the sprocket wheel O⁴ on the shaft L³ and around the sprocket wheel L². P' is a bevel gear pinion secured on the shaft O' and meshing with a bevel gear wheel P² secured on the shaft K. 95

100 When it is desired not to drive the apron L and the carrier N the driving mechanism just referred to is thrown out by means of the clutch mechanism P³ which is of the usual type such as described in reference to the drive of the picking up elevator.

105 The lever Q suitably pivoted on the frame at one end by which the clutch is moved into and out of gear is controlled by means of a rod 7', lever 8' and quadrant 9 as indicated in Fig. 3.

110 R is the end wheel located on the opposite side of the machine to the main wheel and carried on the crank axle R' journaled in a bearing R² secured below the end bar A'. In order to adjust the end wheel R and thereby raise or lower the end of the machine we provide the following simple device: R³ is an arm which is clamped at the lower end to the crank axle and is connected by a rod R⁴ to a lever R⁵ coacting with the quadrant bracket R⁶ secured to the end bar A'. 115

120 We have also provided means whereby the picking up elevator which is located at the front of the machine may be raised and lowered, this of course depending upon the length of the grain in the sheaves or shock, 125 and also prevented from tipping when it contacts with the sheaves or shock. This means consists of the extended bar A³, the fifth wheel S pivotally connected to the end of the same, the cross bar S' secured to the bot- 130

tom of the fifth wheel pivoted on the quadrant brackets S^2 secured to the ends of the cross bar S' , the crank levers S^3 coacting therewith and forming crank axles as shown 5 and the wheels S^4 journaled on the crank axles. It will be seen by manipulating the levers S^3 the front of the extended bar A^3 may be raised and lowered with the crank axle and thereby raise and lower the front of 10 the picking up elevator.

The extended bar A^3 is provided with the driver's seat and the fifth wheel has connected to it the draft tongue S^5 by means of which the machine is driven.

In order to adjust the loading elevator we have provided the following simple device: 15 10 are bars pivotally connected to the ends of the frame as indicated in Fig. 4 and carrying at their upper ends the rollers 11. 12 bare bars secured to the bottom of the bars M of the elevator and forming solid guideways whereby the rollers 11 are confined in 17 their upward and downward movement. 13 is a straddle clip pivotally connected to a lug 14 attached to or forming part of the bar 10. 15 is a rope or chain which extends from the clip 13 and around the axle 16 journaled in the brackets 17 secured to the side boards M . The shaft 16 is provided with a crank handle 30 or handles 17' and has also a ratchet wheel 18 engaged by a spring pressed pawl 19. It will now be seen that by turning the crank handle 17' that the bar 10 may be drawn towards the crank handle and thereby raise 35 the elevator. To lower the elevator it is simply necessary to release the pawl 19. When the elevator is raised to the desired position it will be held securely by the pawl and gage ratchet wheel hereinbefore referred 40 to from falling any lower at the outer end although it may be raised higher if desired.

We have described in detail the construction and arrangement of our improved shock loader in the form which we prefer but it will 45 be understood that this specification is addressed to those skilled in the art and that various changes may be made in the construction and arrangement of the parts without departing from the spirit of our invention.

In order to provide for the two speeds of drive for the picking up prongs we provide the following mechanism: The collar J^3 is provided with a clutch at the opposite end to that hereinbefore described, which meshes 50 with the corresponding clutch formed on the top of the gear wheel J^4 on the shaft K . The gear wheel J^4 meshes with a similar gear wheel J^6 on the counter shaft J^6 suitably journaled in the frame. The shaft J^6 has located 55 60 at its opposite end a sprocket wheel J^7 over which passes the end portion of the sprocket chain J' , the sprocket wheel J^7 being an idler.

It will now be seen that by throwing the clutch J^3 into the position shown in the drawings the drive is thrown from the sprocket

wheel J^2 to the sprocket J , but when the clutch J^3 is thrown so as to engage the clutch on the gear wheel J^4 , the drive is through the gear wheel J^4 and J^6 and J^7 to the sprocket wheel J , the sprocket J^2 in this instance acting 70 as an idler.

What we claim as our invention is:

1. In a shock loader the combination with the main frame and main wheel and end supporting wheel, of an inclined picker elevator 75 located in front of the main frame at one side, a bar A^3 at the opposite side, said bar extending beyond the front of the main frame a fore carriage pivotally connected to the bar A^3 and comprising a cross bar pivotally connected to the end of the bar A^3 , crank levers pivotally connected to the end of the cross bar, coacting toothed quadrants secured to the bar, supporting wheels journaled on the ends of the crank levers and a tongue secured centrally to the cross bar of the carriage as and for the purpose specified. 80

2. In a shock loader the combination with the main frame and supporting wheels, of the inclined picker elevator located in front of the 90 main frame at one side and comprising side boards, upper and lower cross spindles journaled in the side boards, sprocket wheels secured thereon to each side of the elevator, connecting sprocket chains therefor, arc-shaped projections on the upper pair of sprocket wheels, cross bars provided with prongs and pivotally secured to the links of the endless sprocket chains, and arms one on the end of each cross bar designed to ride 100 up onto the arc-shaped projections on the sprocket as the chain revolves as and for the purpose specified.

3. In a shock loader, the combination with the main frame and supporting wheels, of the 105 inclined picker elevator comprising side boards provided with upper and lower longitudinal guiding strips, upper and lower journaled shafts in the side boards, sprocket wheels secured to the shafts, arc-shaped projecting plates secured to the upper wheels and having laterally extending lugs, connecting sprocket chains between the upper and lower wheels, cross bars provided with prongs and extending between the sprocket chains 110 in which they are journaled at their ends, arms extending from the cross bars in the direction of movement of the bars, rollers journaled on the ends of the bars and on the arms and designed to travel in the said guiding 115 strips as and for the purpose specified.

4. In a shock loader, the combination with the main frame and supporting wheels and inclined picker elevator, of a cross conveyer, and elevating conveyer, a supporting strut 125 for the elevating conveyer pivoted at its lower end on the main frame, a roller journaled on the strut in proximity to the end thereof, a bracket forming a guideway secured to the elevating conveyer and designed 130

to receive the roller of the strut, an axle carried by the elevating conveyer, a crank handle for the axle and a flexible connection between the upper end of the strut and the axle as and for the purpose specified.

5. In a shock loader the combination with the main frame and supporting wheels and inclined picker elevator, of a cross conveyer, an elevating conveyer provided with side 10 boards a guideway on the elevating conveyer, a supporting strut for the elevating conveyer pivotally supported at its lower end and having a part designed to engage and have movement in the guide way at its upper end to 15 support the elevating conveyer and means for swinging the strut on its pivot as and for the purpose specified.

6. In a shock loader the combination with the main frame and main wheel and end supporting wheel, picker elevator, cross conveyer and elevating conveyer, of a gear secured to the main wheel, a main shaft journaled on the frame, a pinion secured at one end of the main shaft and meshing with the main gear,

toothed wheels $J^4 J^2$ on the shaft, clutch connections between the toothed wheels a driving sprocket and main shaft, for the picker elevator a connecting sprocket chain between one of the toothed wheels on the main shaft and the driving sprocket of the picker elevator, gear connections between the other toothed wheel on the main shaft and the sprocket chain so as to give the picker elevator two speeds, a bevel gear on the main shaft, a counter shaft, a bevel pinion thereon meshing with the bevel gear on the main shaft, a sprocket on the counter shaft connected thereto by a suitable clutch connection, a sprocket chain connecting the counter shaft and the driving gear of the elevating 40 and cross carriers as and for the purpose specified.

THOMAS ROBSON.
